UNITED STATES PATENT OFFICE

HORACE WALTER DOVER, OF NORTHAMPTON, ENGLAND.

HAND-WHEEL.

1,101,417.

Specification of Letters Patent. Patented June 23, 1914.

Application filed November 8, 1912. Serial No. 730,167.

To all whom it may concern:

Be it known that I, HORACE WALTER DOVER, a subject of the King of Great Britain, and resident of Park Road, St. James 5 End, Northampton, England, managing director, have invented certain new and useful Improvements in Hand-Wheels, of which the following is a specification.

This invention relates to the construction 10 of hand and like wheels and more particularly to the steering hand-wheels of motor cars and the like, which are built up of a peripheral rim, a central hub, and intervening arms; and it has for its object to 15 enable a set of arms, initially independent, to be assembled in such manner as to interlock with one another and with the rim and be so held, by means of bolts, screws or rivets serving to fix them to the hub, as to 20 firmly support the rim concentrically with the hub.

A further object of the invention is to securely attach the outer ends of said arms to the rim by means which permit of the 25 rim itself being made in an economical manner, and at the same time enable the stresses to which the wheel is subjected to be efficiently resisted.

The several arms, which are preferably 30 duplicates of one another, have each an outer end adapted for interlocking engagement with the rim, and an inner end adapted to be superposed upon a surface of the hub (preferably extending at right angles 35 to the axis of the wheel) and to be secured thereto by bolts, screws or rivets (hereinafter referred to as bolts); the inner ends of the arms being so shaped as to interlock one with another and prevent mutual 40 placement in the plane of rotation, while each may be apertured to give passage to a bolt serving on the one hand to hold the arm positively to the hub and on the other hand, in conjunction with a cover-plate 45 which overlies the inner ends of all the arms and conceals the joints whereat they mutually interlock, to assist in clamping one of the adjacent arms to the hub.

Referring to the accompanying drawings, 50 Figure 1 is a plan view of part of one form of steering hand-wheel made in accordance with this invention, parts being removed or shown in section for the sake of clearness. Fig. 2 is a cross section on the line 55 2—2, Fig. 1. Fig. 3 is a similar view to Fig. 1, showing a modification of the invention.

Fig. 4 is a cross section on the line 4—4, Fig. 3. Figs. 5 and 6 are a plan and side elevation respectively of a detail.

In the construction shown in Figs. 1 and 2, the hub *a* is formed integrally with or secured to the end of the shaft whereon the wheel is to be mounted, and is provided with a central (and usually circular) boss *b* serving, when the arms *c* are being assembled, 60 to facilitate and determine the centering and correct positioning of the several arms. The arms *c* are constituted by stampings from sheet metal, and are so bent as to be adapted to retain the rim *d* out of the plane 65 of the hub *a*. Each arm *c* is so formed at its inner end or root as to fit snugly, throughout part of its width as at *e* around the central boss *b*; the root of the arm having at one side of its radial center-line a segmental projection *f* which reaches to about 70 the center of width of the adjacent arm, where the projection is apertured to give passage to the fixing bolt *g*, while at the other side of the radial center-line the root 75 of the arm is voided or cut away to accommodate the lateral projection *f* of the adjacent arm *c* at that side.

Displacement of the arm *c* in the plane of rotation is prevented, as regards movement 80 in one direction, by contact of the segmental lateral projection *f* with the boss *b* on the hub *a* and also by the fixing bolt *g* itself (which acts as a fulcrum to the lever represented by the arm), and as regards movement in the opposite direction, by the fact of the lateral projection *f* being held between the boss *b* on the hub and the contiguous part of the root of the adjacent arm *c* at that side; a heel *h* on this root preferably 90 interlocking, for the sake of greater security, with a recess provided in the lateral projection *f* of the adjacent arm, or vice versa. The inner ends of the several arms *c* are held down to the hub *a* by a cover plate *j* riveted 100 or otherwise secured to the boss *a*.

The outer end of each arm *c*, which may be T-shaped or splayed out laterally at both sides as at *k*, is tongued centrally as at *m* so as to fit into a slot provided at the inner 105 side of the wheel rim *d*, while the pair of lateral shoulders *k* on the arm bear against the rim *d* at the outer ends of the slot.

If desired, the outer ends of each arm may be bifurcated forming a pair of tongues 110 so as to fit into a pair of slots provided at the inner side of the rim *d*, the ends of

the arm in the notch between the pair of tongues bearing against a solid piece left in the rim between the slots.

The rim *d* is made of metal, tubular in form, and it is thickened at its inner side as at *n*, so as to provide the strength and rigidity necessary in view of the strains to which the rim is subjected, more particularly at the points of attachment of the arms.

For this purpose the tube composing the rim is constructed of outer and inner annular members *o* and *p*, each of U-shaped or approximately half-round section, united at the circumferentially extending joints where the edges of the respective members meet; the outer member *o* being of comparatively light section whereas the inner member *p* is thickened as at *n* toward the center of its width.

Each member may be formed from a strip of sheet metal rolled from the flat to the required configuration; the strip constituting the inner member *p* being thicker toward the center of its width and tapering toward the edges. The slots (already referred to) for the attachment of the arms *c* may be formed either before or after the strip is bent to shape.

The edges of the member *p* are stepped inwardly to form circumferential seatings for the edges of the outer member *o* in order that the outer surface of the rim may be flush at each joint. It is preferred to provide a circumferential groove *q* at the outer periphery of the rim, so as to enable an outer coating *r* of protective material such as celluloid, exonite or like material to interlock securely with the metal framework of the rim.

The ends of the rolled strip constituting each member *o* and *p* of the rim *d* are preferably jointed together (to insure continuity of the annulus) by acetylene welding or otherwise, and the two members may be united by welding or soldering at the circumferential joints between them. As, however, the members can not be separated once the inner member *p* has been completed and the outer member *o* has been lapped about the inner member *p* and its own ends joined together, welding or soldering of the circumferential joints may be in some cases dispensed with.

In the modified form of the invention illustrated in Figs. 3 to 6 of the accompanying drawings, the inner ends of the arms *c* are secured to the hub *a*, as hereinbefore set forth, while the outer ends of the arms are secured to the rim in such manner as to permit of the rim being built up of channeled members and a stiffening band, the former being secured by seaming their edges over the edges of the latter, and incased in a protective layer of celluloid, exonite or like material in the form of a spirally-wound length or strip having a plain edge

and a projecting and overlapping edge forming a continuous spiral corrugation on the outside, while at the same time the wheel is adapted to efficiently resist the stresses to which it is subjected. To this end a plate 70 carrying a lug or lugs is secured at one end by riveting or the like inside the inner channeled member of the rim which is perforated to allow of the lug or lugs projecting therethrough, while said plate and channeled member are also perforated to permit of the engagement therewith of the projections from the outer end of the intervening arms to be secured, thus permitting the use of a thin metal rim while at the same time 80 the arms are attached thereto in such manner as to efficiently resist stresses in the plane of rotation and also stresses normal or substantially normal to said plane.

The outer end of each arm *c* is provided 85 toward either side with a pair of fingers *s* and at the center with a finger *s*¹ projecting therefrom, the angles between the fingers *s* and said outer end being rounded as at *t* for a purpose to be hereinafter explained. 90 The rim *d* is built up from two channeled members *o* and *p* and a stiffening band *u*, said channeled members *o* and *p* being secured by seaming their edges over the edges of the stiffening band *u*, as shown, 95 and the outer end of each arm *c* is held by a plate *v* riveted at one end by a rivet or rivets *w* inside the inner member *p* of the rim and carrying a pair of lugs *x* spaced apart and projecting through an aperture in 100 the member *p*, the fingers *s* projecting through apertures in said member and apertures *y* in the plate *v* while the finger *s*¹ projects between the lugs *x* and through the central aperture in the rim member *p*, and 105 the outer end of the arm *c* is riveted or screwed as at *z* between the lugs *x*. In order that the plate *v* may fit closely against the inner surface of the member *p*, it is preferably set back as shown in Fig. 6, and a second piece of metal folded therearound to 110 form the lugs *x*, said second piece of metal lying within the set back portion of the plate *v*.

In making the steering hand-wheel illustrated in Figs. 3 to 6, the plate *v* is first riveted by the rivet *w* to the inner member *p* of the rim in such manner that the lugs *x* normally project through the aperture therein but may be temporarily pressed back 120 therethrough, as shown in dotted lines in Fig. 3; owing to the springiness of the plate *v*; the stiffening band *u* and outer member *o* of the rim are then secured in position and the rim is incased in celluloid, exonite or 125 like material 2 in the form of a length or strip which is spirally wound around said rim, said strip having a plain edge and a projecting and overlapping edge forming a continuous spiral corrugation on the outside. 130

The adjacent edges of the strip abut closely at the inner periphery of the rim a gap being left at the outer periphery, which gap is covered by the projecting and overlapping edge. The edges of the strip are united by a suitable cement or solvent for the celluloid, exonite or like material. Owing to the fact that the lugs α may be pressed back into the body of the rim they present no obstacle to the continuous winding of the strip 2 which is of such width that after it has been wound on the rim and secured an aperture may be cut therethrough without severing the length thereof in order to permit of the lugs α springing out into the required position and consequently to permit of the fingers s^1 passing through said covering. Similarly, the fingers s are of such a size that the apertures cut in the strip 2 do not sever the length thereof. The arms c are then assembled in position and riveted or screwed between the pairs of lugs α , the rounded angles at t forcing aside the celluloid or like covering and bearing against the edges of the apertures in the member p , thus allowing said arms to be more securely fixed than would be the case if their outer ends were to bear against the celluloid or like covering only. The inner ends of the arms c are then secured to the hub a by the cover plate j and rivets or bolts as hereinbefore set forth. In this manner the arms c are securely fixed to a rim constructed and covered in an economical manner, that is to say, although the rim body is made of thin sheet metal only, yet the use of the plates v , lugs α , fingers s and s^1 enables the outer ends of the arms to be attached to the rim in such manner as to efficiently resist, not only the stresses in the plane of rotation, but also the stresses normal or substantially normal to said plane which tend to pull the ends of the arms out of the rim, and which are liable to be set up when the steering hand-wheel of a motor car is gripped and incidentally pulled upward when driving the car.

In the event of its being required to mount upon the wheel shown in Figs. 1 and 2, or Figs. 3 to 6, the usual quadrant fittings, for such purposes as the control of the car, the arms c , which are formed of stampings which are in all respects identical with one another, may have screwed, riveted or otherwise fixed to them, suitable bosses (not shown) adapted to carry the fittings in question.

When, as above set forth, the arms are used in connection with steering wheels for motor cars, wherein the rim of the wheel consists of a metal body covered with a protective layer of celluloid, exonite or like material, the arms, hub, and cover-plate may also, if desired, be covered with a protective layer of similar material, or if desired, some of such parts may be made of polished

brass and other parts coated with the protective layer.

Claims—

1. A wheel comprising a rim, a central hub having a boss thereon, a plurality of separate arms intervening between said rim and said hub, the outer end of each of said arms being adapted for interlocking engagement with said rim, while the inner end of each of said arms is shaped and adapted to fit snugly throughout part of its width around said boss, each arm having at its inner end a segmental portion constituting a lateral projection extending at one side of the radial center line of the arm to about the center of width of the adjacent arm, the inner end of each arm being cut away at the other side of the radial center line and adapted to accommodate the lateral projection of the adjacent arm at that side. 85

2. A wheel comprising a rim constructed of an outer and an inner channeled member, a hub, a plurality of separate arms intervening between said rim and said hub, a plate secured at one end inside said inner channeled member of the rim and having a lug thereon, said inner channeled member being perforated and said lug being adapted to project through said inner channeled member, said plate and said inner channeled member being also perforated, each of said intervening arms having projections on the outer end thereof, said projections being adapted to project through said perforated inner channeled member and said perforated plate. 100

3. A wheel comprising a rim, a central hub having a boss thereon, a plurality of separate arms intervening between said rim and said hub, the outer end of each of said arms being adapted for interlocking engagement with said rim, while the inner end of each of said arms is shaped and adapted to fit snugly throughout part of its width around said boss, each arm having at its inner end a segmental portion constituting a lateral projection extending at one side of the radial center line of the arm to about the center of width of the adjacent arm, the inner end of each arm being cut away at the other side of the radial center line and adapted to accommodate the lateral projection of the adjacent arm at that side, the inner end of each arm having a heel on that side of the center line thereof opposite to the lateral projection, each of said lateral projections being recessed to accommodate the heel on the adjacent arm. 115

4. A wheel comprising a rim, a central hub having a boss thereon, a cover plate on said hub, a plurality of bolts adapted to secure said cover plate to said hub, a plurality of separate arms intervening between said rim and said hub, the outer end of each of said arms being adapted for interlocking 130

engagement with said rim, while the inner end of each of said arms is shaped and adapted to fit snugly throughout part of its width around said boss and adapted to be clamped between said hub and said cover plate, each arm having at its inner end an apertured segmental portion through which one of said bolts passes and which constitutes a lateral projection extending at one side of its radial center line to about the center of width of the adjacent arm, the inner end of each arm being cut away at the other side of the radial center line and adapted to accommodate the lateral projection of the adjacent arm at that side.

5. A wheel comprising a rim constructed of an outer and an inner channeled member, a hub, a plurality of separate arms intervening between said rim and said hub, a 20 plate secured at one end inside said inner channeled member of the rim, said plate

having lugs thereon, said inner channeled member being perforated and said lugs being adapted to project through said inner channeled member, said plate and said inner channeled member being also perforated, each of said intervening arms having a pair of fingers projecting from the outer end thereof, the angles between said fingers and the end of the arm being rounded, said 30 fingers being adapted to project through said perforated inner channeled member and said perforated plate, the rounded angles between said fingers and the end of the arm being adapted to engage the edges 35 of the perforations in said inner channeled member.
